UNITED STATES PATENT OFFICE.

HOWARD M. DU BOIS, OF DETROIT, MICHIGAN, ASSIGNOR TO PENNSYLVANIA SALT MANUFACTURING COMPANY, A CORPORATION OF PENNSYLVANIA.

ELECTROLYTIC CELL.

1,178,501.

Specification of Letters Patent. Patented Apr. 11, 1916.

Application filed April 11, 1910. Serial No. 554,604.

To all whom it may concern:

Be it known that I, HOWARD M. DU BOIS, a citizen of the United States of America, residing at Detroit, in the county of Wayne 5 and State of Michigan, have invented certain new and useful Improvements in Electrolytic Cells, of which the following is a specification, reference being had therein to the accompanying drawings.

10 The invention relates to apparatus for the electrolysis of salts, and consists in the novel construction as hereinafter set forth.

In the drawings—Figure 1 is a vertical central section through one of the cells; Fig. 15 2 is a horizontal section thereof.

My improved construction is particularly designed for use in a continuous process of electrolysis, where the electrolyte is constantly fed into the anode chamber and the 20 cathode liquor is constantly removed. Low electrical resistance and high efficiency is maintained by providing an overflow communication between the anode and cathode compartments. This prevents the clogging 25 of the cell, due to the filling of the pores of the diaphragm with impurities, and permits the electrolyte to find access to the cathode compartment over the diaphragm. The passageway between the two compartments 30 is so formed as to be constantly sealed with liquid, which prevents the passage of the gaseous products of the electrolysis therethrough.

In detail, the cell is composed of a series 35 of segmental metallic plates A, which are bolted or otherwise secured to each other to form a cylindrical outer casing, and which also constitutes the cathode.

B is a non-metallic head at the bottom of 40 the cell around which the plates A are clamped.

C is a cylindrical porous diaphragm 45 formed of asbestos or other material, and extending around the cell adjacent to the inner face of the segment A.

D is a ring of insulating material secured to the upper end of the diaphragm and extending upwardly therefrom, being preferably flared outward, as shown. E and F 50 are rings also of insulating material arranged respectively outside and inside of the ring D, leaving a space therebetween. The outer ring E rests upon a bearing on the members A and the inner ring is supported

from the outer ring by a laterally-extending flange G.

H is an anode formed of a series of carbons arranged around the cell inside of the diaphragm, their upper ends passing out through a ring I which in connection with a dome-shaped member J, constitutes the cover of the cell. The member J engages the member I, and may have its joint therewith and with the off-take pipe K sealed with any suitable cement, said member J also preferably having a depending flange L, which protects the cement from the corrosive action of the condensed chlorin vapor collecting in the dome.

As has been stated, the diaphragm C is arranged adjacent the inner face of the segments A. These segments are, however, provided with longitudinally-extending grooves M, which form channels connecting the upper end of the cell with a channel in an annular member N at the lower end of the cell. Thus, the cathode surface is greatly increased by these grooves, and the free flow of the liquor is permitted.

With the construction as described in use, the electrolyte is fed into the anode compartment by a suitable conduit O which, as shown, enters the center of the body of the cell. The required pressure for maintaining a flow is produced by a hydrostatic column P without the cell, having a vertically-adjustable overflow Q. Thus, where the proper adjustment is made, the liquid will flow constantly into the anode compartments, and there will be a constant overflow from the anode to the cathode compartment through the channel formed by the rings, E, F and D. The electrolyte, after passing this channel, flows downward through the grooves M, where it is still in the electrolytic field intermediate the cathode and the anode. Thus, the electrolysis and exchange of ions will constantly take place through the porous diaphragm, where the supply of liquid is maintained by the overflow above the diaphragm.

The chlorin gas accumulating in the anode will rise to the top of the cell, but will not pass through the channel between the rings D, E and F, as these are arranged, as shown, to form a trap. In the same way, hydrogen gas, accumulating in the cathode, will rise into the space between the rings

E and F, but is prevented from access to the anode compartment.

The constant inflow of the electrolyte and the overflow above the screen will cause a constant discharge into the annular channel N at the lower end of the cell. The liquor thus discharged must pass through the entire electrolytic field, and, consequently, it contains a highly concentrated product of the electrolysis.

Where the cell is employed for electrolyzing chlorin salts, a certain amount of the hypochlorite salts is always formed, and as this product has a highly destructive action upon the cathode, it is desirable to eliminate the same, and this I have accomplished by passing the overflow liquid into the path of the hydrogen liberated from the cathode. The hypochlorite will be converted into a chlorid before it can injure the cathode.

The formation of the cap or cover of the cell with a separable section J prevents injury to the anode in case of gas explosions.

It is practically impossible to always maintain complete separation between the hydrogen and chlorin gases, and where a mixture occurs an explosion will follow. In such an event, however, the force of the explosion will merely blow off the dome-shape cap J without disturbing the ring I or the anode connected thereto.

What I claim as my invention is:—

1. In an electrolytic cell, the combination with a vertically-arranged diaphragm, of an anode and a cathode arranged upon opposite sides of said diaphragm in proximity thereto, means for constantly feeding the electrolyte into the anode compartment, and a gas-proof liquid communication channel for permitting the surplus electrolyte to pass over said diaphragm and flow between the same and the cathode.

2. In an electrolytic cell, the combination with a vertically arranged diaphragm, of a cathode adjacent said diaphragm provided with a vertical flow channel therebetween, means for liquid communication above said diaphragm from one side thereof to the other, and means for preventing the passage of the gas through said liquid communication.

3. In an electrolytic cell, the combination of an annular diaphragm, an annular cathode surrounding said diaphragm having a series of vertically-extending grooves or channels on the inner face thereof, an outlet conduit connecting with the lower ends of said channels, and a gas sealed means of liquid communication at the upper end of said diaphragm.

4. In an electrolytic cell, the combination of an annular diaphragm, an annular cathode surrounding said diaphragm, and an annulus of insulating material at the upper

end of said diaphragm providing a gas-proof means of liquid communication on opposite sides of the diaphragm.

5. An electrolytic cell, comprising an annular cathode, an annular diaphragm adjacent thereto, and a gas-proof seal above said diaphragm providing liquid communication between opposite sides thereof. 70

6. In an electrolytic cell, a cathode formed of a plurality of cylindrical segments having vertically-extending channels therein, a diaphragm adjacent said cathode, a bottom plate clamped in position by said segments, an annulus at the upper end of said diaphragm, providing means of liquid communication between opposite sides thereof, and an annular channel at the lower end of said cell in communication with the vertical channels in said cathode. 75

7. In an electrolytic cell, the combination with a cylindrical diaphragm, of a cylindrical cathode surrounding said diaphragm and providing a flow passage therebetween, and a plurality of rings at the upper end of said cell forming a gas-proof liquid communication between the opposite sides of said diaphragm, said rings being formed of insulating material. 85

8. An electrolytic cell, comprising a vertically-arranged anode, cathode and porous diaphragm therebetween providing a flow passage between the diaphragm and the cathode, a sealed bypass for the electrolyte over the porous diaphragm, and a discharge for the cathode liquor communicating with the lower end of the space between the cathode and the diaphragm. 95

9. An electrolytic cell comprising a cathode, a diaphragm adjacent thereto, and a gas-proof seal above said diaphragm providing liquid communication between opposite sides thereof. 105

10. An electrolytic cell having an annular base ring with a groove or channel therein for the cathode products, and a cell supported on said ring and having a cathode member arranged to discharge into said channel, substantially as described. 110

11. An electrolytic cell having an annular base ring with a groove or channel therein for the cathode products, and a cell supported on said ring and having a cathode member formed with a plurality of vertical flow channels arranged to discharge into said channel, substantially as described. 115

12. In an electrolytic cell, a base ring having a vertical opening through its central portion and also having an annular groove in its upper surface, a cylindrical cathode, a cell bottom supported on said base, and a supply-pipe for electrolyte extending upwardly through the opening of the base and into the cell, substantially as described. 125

13. An electrolytic cell having a dia- 130

phragm surrounding the anode compartment of the cell, and a cathode member surrounding the diaphragm, there being an overflow passage for the electrolyte from the anode to the cathode compartments of the cell above the upper edge of said diaphragm, substantially as described.

14. An electrolytic cell having a diaphragm surrounding the anode compartment of the cell, a cathode member surrounding the diaphragm, there being an overflow passage for the electrolyte from the anode to the cathode compartments of the cell above the upper edge of said diaphragm, 10 there being also a plurality of vertical flow channels between the diaphragm and cathode member, which communicate with said overflow, and the base portion of the cell having an annular trough to receive the discharge from said channels, substantially as described.

15. An electrolytic cell having a dia-

phragm surrounding the anode compartment of the cell, a cathode member surrounding the diaphragm, there being an overflow passage for the electrolyte from the anode to the cathode compartments of the cell above the upper edge of said diaphragm, 20 there being also a plurality of vertical flow channels between the diaphragm and cathode member, which communicate with said overflow, and the base portion of the cell having an annular trough to receive the discharge from said channels, substantially as described.

25 In testimony whereof I affix my signature in presence of two witnesses:

HOWARD M. DU BOIS.

Witnesses:

NELLIE KINSELLA,

JAMES P. BARRY.
